TO ARNOLD ELECTRIC COMPANY, OF RACINE, WISCONSIN, A CORPORATION OF WIS-
CONSIN.

DRINK MIXER.

Application filed February 11, 1924. Serial No. 691,991.

To all whom it may concern:

Be it known that we, RUSSELL A. BLISH and STEPHEN J. POPLAWSKI, citizens of the United States, and residents of Racine, in the county of Racine and State of Wisconsin, have invented certain new and useful Improvements in Drink Mixers, of which the following is a full, clear, concise, and exact description, reference being had to the accompanying drawings, forming a part of this specification.

This invention relates to drink mixers such as are used to mix the ingredients of beverages served as soda fountains.

In prior practice, it has been common to fix the agitator shaft to the motor shaft. When the drink mixing receptacle is removed from a mixer of this type, it leaves the agitator shaft, with the ingredients of the drink thereon, exposed to dust, flies, and other insects in the atmosphere, thus providing a medium by which disease germs may readily be communicated to the consumers of the drinks mixed.

There is another objection to the fixed agitator type of mixer. The agitator should extend nearly to the bottom of the mixing receptacle. It is necessary, therefore, that the agitator project about six inches from the motor. As the motor is driven at a speed of approximately 10,000 to 12,000 R. P. M., any deviation of the agitator from true will cause vibration of the agitator. If the agitator is greatly out of true, the vibration is very great, oftentimes causing the entire mixing apparatus to vibrate and creep along the counter. This violent vibration of the agitator rapidly ruins the motor bearings, making it necessary to send the mixer to the shop for repairs. Not only does the vibration wear out the bearings, but as a large portion of the energy of the motor is used up in causing the vibration, the speed of the agitator is slowed down very materially.

As soon as the bearings in the motor become slightly worn, the vibration also causes a very decided rattling or chattering. Even though the agitator shaft is properly trued before the mixer leaves the factory, the operator in handling the mixer and an placing

the receptacle into and removing it from its operative position, almost invariably springs the agitator before the mixer has been long in use, thus requiring that the device be overhauled and the shaft trued up. It is found that of the mixers returned to the shop for repairs, about 90% have been rendered defective on account of the shaft getting out of true.

As the agitator of the present invention is provided with a bearing at the lower end thereof, the vibration of the shaft above referred to is prevented, thus causing it to run quietly without vibration, and greatly increasing the life of the mixer.

The object of the present invention is to provide an improved sanitary drink mixer of the type in which the agitator and agitator shaft are removable with the drink mixing receptacle, and which may be operated as easily as are the mixers of the fixed agitator shaft type.

One of the features of the present invention is the frame mounted on one side of the receptacle for supporting the agitator shaft, and so arranged that there will be sufficient unobstructed opening at the top of the mixing container to permit the ingredients of the drink readily to be placed in the container, even when in operative relation to the motor, and the drinks poured from the container without removing the agitator from the receptacle.

Another feature of the invention resides in the bearing provided to support the lower end of the agitator shaft.

A further feature of the invention is the displaceable guide member which permits the receptacle with the agitator shaft thereon to be forced upwardly into operative position and which serves firmly to hold the receptacle on its support during operation of the agitator.

A further feature of the invention lies in the provision of a mixer having an agitator which is mounted in and is removable with the mixing receptacle and is equipped with a separable connection to the motor shaft, of a switch for controlling the motor and automatically actuated by manual movement of the receptacle itself when disposing the

receptacle and said separable connection in, and removing them from, operative positions.

Other features and advantages will appear from time to time as the description of the invention progresses.

It is believed that further disclosure of the invention will be understood most readily from a detailed description thereof taken in connection with the accompanying drawings, in which—

Figure 1 is a side view of the drink mixer with parts broken away to show the agitator within the mixing receptacle and the clutch mechanism by means of which the agitator shaft is coupled to the motor shaft;

Figure 2 is a view of the agitator shaft and its frame removed from the mixing receptacle;

Figure 3 is a plan view of the frame disclosed in Figure 2, showing it in position on the edge of the receptacle;

Figure 4 is a section on line 4—4 of Figure 1, and

Figure 5 is a section on the line 5—5 of Figure 1.

Referring now to the drawings, in which like reference characters indicate like parts in the several views, 10 is the base of the mixer to which is secured the upwardly extending standard 11. Fixed to the standard 11, adjacent to the upper end thereof, is an electric motor 12 of the usual or any desired type. Motor 12 is provided with a downwardly extending shaft 13. Fixed to the shaft 13, by means of the set screw 14, or any other desired manner, is the sleeve 15, the lower end of which has the longitudinally extending opening 16 thereto in adapted to receive the substantially triangular upper end 17 of the agitator shaft 18. The sleeve 15 with its opening 16 and the upper end 17 of shaft 18 form the cooperating coupling members for the motor shaft and the agitator shaft, respectively, which permit the shafts readily to be joined or separated from each other.

The motor 12 is provided with the downwardly extending collar 19 to which is secured, by means of the set screw 20, the sleeve 21. Slidable within the sleeve 21 is a second sleeve 22. The sleeve 21 is provided with the inwardly directed flange 23, and sleeve 22 with the outwardly directed flange 24, which are adapted to limit the downward movement of the sleeve 22 relative to sleeve 21. A spring 25 is positioned between the upper end of the sleeve 22 and the collar 19 and tends normally to force the sleeve 22 downwardly. Sleeve 22 is of a size snugly to fit the sleeve 15 which forms the coupling member carried at the lower end of the motor shaft 13.

At 26 is shown the drink mixing receptacle or container, to one side of which is

secured the supporting frame 27 for the agitator shaft 18. The supporting frame 27 may be secured to the receptacle 26 in any desired manner, but in the form herein disclosed, the support 27 is provided adjacent to the upper end thereof with the outwardly and downwardly extending finger 28 between which and the body of the support 27 the upper edge of the receptacle 26 is adapted snugly to be received. The finger 28 may very conveniently be formed by stamping it out of the body of the support 27. The receptacle 26 is provided with a plurality of longitudinally extending inwardly directed beads 9 which assist in preventing the liquid of the drink from swirling over the edge of the container. In certain instances, it may be found desirable to position the support 27 over one of the beads 9, as shown in Figure 5. When thus arranged, the support 27 may be transversely curved so as to conform substantially to the bead 9.

Secured to the laterally extending flange 29 of the support 27, in any desired manner, is a bearing 30 provided with the upwardly and inwardly curved fingers 31 adapted partially to surround the ball 32 formed at the lower end of the shaft 18. The support 27 at the upper end thereof is provided with the laterally extending flange 33 within which is secured the sleeve or collar 34 provided with an opening through which the upper end of the agitator shaft 18 extends. The outer surface of the collar 34 is tapered so as snugly to engage the tapered edge of the sleeve 22.

Secured to the agitator shaft 18 are the agitator elements 35 which, in the preferred embodiment of the invention, comprise the discs which are corrugated, the corrugations extending radially of the discs. This form of agitator element has been found to be vastly superior to the propeller type in that it causes the drink to be aerated, thus producing a foam on the finished drink, while the propeller type of agitator cuts through the liquid instead of aerating it and produces an inferior drink.

Pivots joined to the standard 11, by means of the pivot pin 36, is the receptacle support 37 provided with the laterally extending flange 38 adapted to underlie the bottom of the receptacle to hold the triangular upper end 17 of the agitator shaft 18 in operative relation to the clutch member 15 fixed to the motor shaft 13.

Insulatively mounted within the standard 11 is a pair of springs 39 and 40 which are arranged to control the circuit for the motor 12. When springs 39 and 40 are in engagement, the motor circuit is closed, but when the springs 39 and 40 are separated, the circuit for the motor is broken.

Carried by the receptacle support 37 is

a pin 41 which passes through the opening 42 in standard 11 and into engagement with the block 43 of insulating material secured to spring 39. The tension in the spring 39 is such that when the receptacle 26 is not resting on the supporting flange 38, the pin 41 will be forced to the right, as viewed in Fig. 1, so as to separate the spring 39 from spring 40. When, however, the weight of the receptacle is placed on the supporting flange 38, the support 37 will rotate slightly about its supporting pin 36, thus causing contact spring 39 to move into engagement with contact spring 40 and closing the circuit for the motor.

The operation of the device is as follows:

When it is desired to mix a drink, the receptacle will ordinarily be placed on the counter and the several ingredients comprising the drink placed therein.

The operator will then grasp the receptacle with the agitator shaft therein, and place it in position. In doing so, the tapered member 34 which surrounds the upper end of the agitator

shaft 18 will be placed within the tapered end of the sleeve 22. If the side of the receptacle to which the agitator is secured is positioned against the support 37 and slid upwardly thereon, it will guide the member

34 into the sleeve 22. The receptacle will now be forced slightly upwardly to compress the spring 25, thus permitting the substantially triangular upper end 17 of the agitator shaft to be placed within the opening 16 in the coupling member 15 secured

to the end of the motor shaft 13. The lower end of the receptacle will now be moved slightly toward the standard 11 to position it upon the flange 38 at the lower end of the

receptacle support 37. Upon releasing the receptacle, the support 37 will tilt slightly to the left, as viewed in Figure 1, and force spring 39 into contact with spring 40, thus closing the circuit of the motor 12.

The motor will now be started into operation and the rotary movement of the shaft 13 will be communicated to the agitator shaft through the medium of the coupling members 15 and 17.

It will be noted that the engagement of the tapered surface of the collar 34 with the sleeve 22 acts to center the agitator with respect to the motor shaft or spindle, and direct the coupling member 17 on the agitator shaft into the opening 16 of the coupling member 15 on the motor shaft. The sleeve 22 and spring 25 form a resilient connection between the agitator parts and the motor which not only assists in centering

the agitator shaft in respect to the motor shaft, but also acts by its constant pressure to maintain the parts snugly in position and thus tends to prevent vibration and rattling of the apparatus.

After the ingredients of the drink have

been sufficiently mixed, the receptacle will be removed by forcing it slightly upwardly against the tension of the spring 25, then moving the lower end thereof outwardly so as to disengage it from the laterally extending flange 38 when it can be removed from the mixer, in an obvious manner. As soon as the weight of the receptacle is removed from the support 38, spring 39 will act to move the pin 41 to the right, as viewed in Figure 1, thus separating springs 39 and 40, and opening the circuit of the motor 12.

By reference to Figure 1 of the drawings, it will be noted that the motor 12 is so mounted that the shaft 13 thereof is inclined slightly to the vertical. It will also be noted that the agitator shaft 18 is substantially parallel to one side of the receptacle and is so positioned as to align with the shaft 13. By placing the agitator adjacent to the side of the receptacle toward the supporting standard, the agitator shaft may be readily placed in alignment with the motor shaft without necessitating mounting the motor greatly to one side of the supporting standard.

It is customary, whenever the drink mixing receptacle is removed from the mixer after a drink has been mixed, to wash the receptacle by plunging it into a tank of water. In the present device, as the agitator and agitator support are carried by the receptacle, they are cleansed whenever the receptacle is thus washed. Furthermore, it will be noted that the support carrying the agitator shaft is readily removable from the receptacle, thus permitting a more thorough cleansing of the receptacle and the agitator parts whenever desired.

In drink mixers in which the agitator and shaft are concentrically disposed in the receptacle, the operation of the agitator tends to cause a swirling of the contents of the receptacle, which will produce a deep vortex at the center of the receptacle, tending to cause the contents to rise up along the walls and over the upper edge of the receptacle. As the agitator shaft of the present invention is arranged eccentrically of the receptacle and substantially parallel to one side thereof, there is much less tendency to cause the vortex above referred to, and the contents of the receptacle are much more thoroughly agitated.

As the present device requires that the lower end of the receptacle be tilted only slightly away from the base in order to release it from the mixer, there is much less danger of spilling the contents of the receptacle when removing it from or placing it in operative relation to the mixer than occurs when the receptacle must be moved downwardly materially in order to free itself from the lower end of the downwardly projecting agitator shaft.

It is desirable that a drink mixer be so constructed that the operator may insert the receptacle in the mixer and remove it therefrom by the use of only one hand. Due to 5 the slight movement required to disengage the receptacle from the mixer, this operation may be more readily performed by the operator than with devices heretofore produced.

When the receptacle or container 26 and 10 its connected agitator are disposed in operative position, as illustrated in Figure 1, the spring 25 exerts a downward pressure which serves firmly to hold the receptacle 26 on the flange or shelf 38 of the support 37. 15 The said spring 25, assisting the weight of receptacle 26 and its contents, also serves more positively to hold the motor circuit controlling contacts closed.

It is to be understood that applicants 20 contemplate many modifications in the various details of the device shown in the present application. A coupling may be employed which differs materially in detail from that herein shown. Different means may be employed 25 for securing the agitator shaft support to the receptacle. A different type of motor-controlling switch and different means for operating it may be employed. Other variations in the details of applicants' 30 device will readily suggest themselves to those skilled in the art. The invention, therefore, should be limited merely by the scope of the appended claims.

Having thus described our invention, 35 what we claim as new and desire to secure by Letters Patent of the United States is:

1. In a drink mixer, the combination with an electric motor and its shaft, of a standard for supporting said motor in fixed relation to a suitable base, a receptacle, a support for said receptacle relatively movable with respect to said motor when said receptacle is placed thereon, a rotatable agitator detachably mounted in said receptacle and supported independently of said motor, coupling members upon the agitator and motor shaft for operative engagement with and disengagement from one another, yielding means associated with the motor shaft 45 for guiding and centering the agitator relative to the motor shaft and for pressing the container against the support, and a switch controlled by movement of said support adapted automatically to close the motor circuit when normal operative relationship 50 is established between said agitator and said motor shaft, and to open the motor circuit when such relationship is disestablished.

2. In a drink mixer, the combination with 60 an electric motor having a substantially vertical shaft, of a support for said motor, a receptacle, a support for said receptacle, a rotatable agitator mounted on the side wall and in said receptacle and with the receptacle constituting a structural unit, cou-

pling members upon the agitator and motor shaft for operative engagement with and disengagement from one another, and means for guiding and centering the agitator relative to the motor shaft. 70

3. In a drink mixer, a receptacle, an agitator support within said receptacle and secured to the wall thereof, an agitator, a thrust bearing carried by said support in which the lower end of said agitator is rotatably mounted, a motor, and means for detachably coupling said agitator to said motor. 75

4. In a drink mixer, a receptacle, an agitator, an agitator support, a spring clip 80 carried by said support adjacent to the upper end thereof for engaging the upper edge of said receptacle, a bearing carried by said support in which said agitator is rotatably mounted, a motor, and means for detachably coupling said agitator to said motor. 85

5. In a drink mixer, a receptacle, an agitator, an agitator support comprising a member extending substantially parallel to one side of said receptacle and adjacent thereto, a finger carried by said support passing over the upper edge of said receptacle and engaging the outer side thereof, whereby the edge of said receptacle is clamped between said finger and said support, a bearing carried by said support in which said agitator is rotatably mounted, a motor, and means for detachably coupling said agitator to said motor. 90 95

6. In a drink mixer, the combination with a motor and its shaft, of a support for said motor, a receptacle, a rotatable agitator mounted in said receptacle and supported thereby independently of said motor, coupling members on said shaft and agitator respectively for operatively engaging and disengaging them, and yielding means associated with the coupling device adapted to press the receptacle against the support. 100 105

7. In a drink mixer, the combination with an electric motor and its shaft, of a standard for supporting said motor in fixed relation to a suitable base, a receptacle, a rotatable agitator mounted in said receptacle and supported thereby independently of said motor, coupling members on said shaft and agitator respectively for operative engagement with and disengagement from one another, and a resiliently supported centering guide for directing one of said members into operative relation to the other and for urging the receptacle downwardly relatively to the standard. 110 115 120

8. In a drink mixer, the combination with an electric motor and its shaft, of a support for said motor, a receptacle, a rotatable agitator mounted on the side wall and in said receptacle and supported thereby independently of said motor, coupling means including a yielding connection between said 125 130

- agitator and motor for separably joining said shaft and agitator, and a switch adapted automatically to close the motor circuit when normal operative relationship is established between said agitator and said shaft, and to open the motor circuit when such relationship is disestablished.
9. In a drink mixer, a receptacle, an agitator, an agitator support comprising a member extending substantially parallel to one side of said receptacle and adjacent thereto, a finger carried by said support adapted to engage the outer side of said receptacle whereby the edge of said receptacle is clamped between said finger and said support, a longitudinally extending inwardly directed bead in said receptacle, said support being arranged in engagement with said bead, a bearing carried by said support in which said agitator is rotatably mounted, and means for detachably coupling said agitator to said motor.
10. In a drink mixer, a receptacle, an agitator, an agitator support comprising a member extending substantially parallel to one side of said receptacle and adjacent thereto, a finger carried by said support adapted to engage the outer side of said receptacle whereby the edge of said receptacle is clamped between said finger and said support, the material of said receptacle being pressed inwardly to form a longitudinally extending bead on the inside thereof, and a corresponding groove on the outside thereof, said support being arranged in engagement with said bead, said finger being adapted to overlie said groove, a bearing carried by said support in which said agitator is rotatably mounted, and means for detachably coupling said agitator to said motor.
11. In a drink mixer, a motor, a shaft extending downwardly from said motor, a coupling member at the lower end of said shaft, a mixing receptacle, a support within said receptacle and supported thereby, an agitator rotatably mounted in said support, a coupling member on said agitator arranged to co-operate with said first mentioned coupling member whereby said agitator is joined to said shaft, said support, agitator and coupling member carried thereby being so arranged as not to materially obstruct the top opening of said receptacle.
12. In a drink mixer, a motor, a shaft extending downwardly from said motor, a coupling member at the lower end of said shaft, a mixing receptacle, a support within said receptacle and supported thereby, an agitator rotatably mounted in said support, a coupling member on said agitator arranged to co-operate with said first mentioned coupling member whereby said agitator is joined to said shaft, said support, agitator and coupling member carried thereby be-
- ing arranged at one side of a diameter of 65 the top of said receptacle.
13. In a drink mixer, a motor, a shaft extending downwardly from said motor, a coupling member at the lower end of said shaft, a mixing receptacle, a support within said receptacle and supported thereby, an agitator rotatably mounted in said support, a coupling member on said agitator arranged to co-operate with said first mentioned coupling member whereby said agitator is joined to said shaft, said support, agitator and coupling member carried thereby being arranged adjacent to one side of said receptacle.
14. In a drink mixer, a motor, a shaft extending downwardly from said motor, a coupling member at the lower end of said shaft, a mixing receptacle, a support within said receptacle and supported thereby, an agitator rotatably mounted in said support, a coupling member on said agitator arranged to co-operate with said first mentioned coupling member whereby said agitator is joined to said shaft, said support, agitator and coupling member carried thereby being arranged eccentrically of said receptacle.
15. In a motor driven mixer, the combination with a supporting column, of a motor switch associated with said column having an operating button projecting therefrom, and a container support in the path of said button and movable under the influence of the weight of its container to actuate said switch, a container-agitator unit comprising a container adapted for disposition on said support and an agitator comprising bearings mounted on and in said container, said agitator being adapted to be manipulated into detachable driven relation to said motor when the container is placed on said support and resilient coupling means acting between the motor and the agitator resiliently urging the container-agitator unit forward the aforesaid container support.
16. In a motor driven mixer, the combination with a supporting column, a motor carried thereby, a motor switch mounted within said column and having an operating button projecting therefrom, and a container support pivoted at its upper end to said column and having an intermediate portion in the path of said button, said container support being movable to push said button inwardly to actuate the switch upon the placing of a container thereon, and a mixing unit comprising a container and an agitator mounted therein, co-operating clutch members on said agitator and motor respectively adapted to maintain a driving engagement therebetween in all positions of said container support, and a spring-pressed sleeve associated with one of said clutch members for centering and guiding the agitator relatively

to the motor and for urging the mixing unit downwardly relatively to the aforesaid container support.

17. A drink mixer comprising two principal and co-operating units, namely, a supporting and driving unit and a container-agitator unit; said supporting and driving unit comprising a standard, a container support, and a motor disposed above said support; said container-agitator unit comprising an open-top container and an agitator in and connected to said container and adapted to maintain its position on and in said container in all positions which the latter may assume during rinsing or in the manipulation of the container-agitator unit onto or off of the supporting and driving unit; and co-operating clutch members associated with the motor and agitator respectively adapted to effect a detachable driving connection between the motor and agitator when the container is placed on the aforesaid support.

18. A drink mixer comprising two principal and separable cooperating units, namely, a container-agitator unit and a supporting and driving unit; said container-agitator unit comprising an open top container, agitator bearings firmly carried on said container and a rotatable agitator journaled in said bearings and located in said container and wholly above the bottom thereof, said agitator and bearings being adapted to maintain their positions on and in the container in all positions which the latter may assume during the rinsing or when in use; said supporting and driving unit comprising a standard, a container support on said standard and a motor disposed a substantial distance above said support; cooperating clutch members associated with the agitator and motor respectively adapted to effect the detachable driving connection between the motor and agitator when the container is disposed on the aforesaid support, and a resilient guiding and centering device associated with the motor carried clutch member and serving yieldingly to urge the container-agitator unit downwardly.

19. In a drink mixer a container-agitator unit comprising an open top container, agitator bearings firmly carried on said container, an agitator held in said bearings for rotation therein, and one of a pair of cooperating clutch members carried at the upper end of said agitator; and a supporting and driving unit comprising a container support, an electric motor disposed a substantial distance above said support, the other of said pair of cooperating clutch members carried by the motor, means automatically closing the motor circuit when the container-agitator unit is placed in operative relation to the supporting and driving unit and spring means associated with one of the

clutch members tending to press the container-agitator unit downwardly relatively to the supporting and driving unit.

20. A drink mixer comprising two separable cooperating units namely a container-agitator unit and a supporting and driving unit; the container-agitator unit comprising an open top container, an agitator bearing structure firmly but detachably mounted on and in said container, an agitator held in said bearing structure for rotation therein and located wholly above the bottom of said container, said bearing structure and agitator normally being adapted to maintain their positions on and in the container irrespective of the position which the latter may assume during rinsing or use, and one of a pair of cooperating clutch members at the upper end of said agitator; said supporting and driving unit comprising a container support, a motor disposed above said support and the other of the aforesaid pair of cooperating clutch members carried by said motor.

21. In a drink mixer, an open top container, an agitator bearing structure, an agitator held in said bearing structure for rotation therein, means at the top of said agitator for facilitating its connection with an overhanging motor, said bearing structure being firmly held on the wall of said container, whereby, regardless of the positions assumed by the container during rinsing or use, all of the aforesaid elements may be manipulated as a unit by grasping the container, a container support and an overhanging motor adapted for detachable driving connection with said agitator.

22. In a drink mixer, a driving unit comprising an overhanging motor and its support and a container-agitator unit, said container-agitator unit comprising an open top receptacle, having therein an agitator adapted to have its upper end detachably connected in driven relation to said motor, said agitator being connected with said receptacle so as to maintain its position on and in the receptacle in all positions which the latter may assume during rinsing or use.

23. In a drink mixer, a container-agitator unit comprising an open top receptacle having a rotatable agitator disposed therein and connected thereto for manipulation with and by the receptacle in all positions which the receptacle may assume during rinsing or use, said agitator being adapted to have its upper end detachably connected with a driving motor.

24. In a drink mixer, a container-agitator unit comprising an open top receptacle having a rotatable agitator disposed therein and located immediately adjacent to its side wall, whereby the top opening of the receptacle is not materially obstructed by the agitator, said agitator arranged to have its upper end

detachably connected to a driving motor and being so connected to the receptacle as to be manipulated by and with the receptacle in all positions which the latter may assume 5 during rinsing or use.

25. In a drink mixer, an open top receptacle having disposed adjacent the inner surface of its side wall an agitator shaft bearing structure, a rotatable agitator shaft held 10 and journalled by said bearing structure, said agitator shaft being arranged to have its upper end operatively detachably connected with a driving motor, and means detachably but firmly connecting the said bearing structure to the receptacle whereby 15 said bearing structure and the agitator shaft may be manipulated by and with the receptacle in all positions which the latter may assume during rinsing or use.
20. 26. In a drink mixer, a supporting and driving unit comprising a fixed overhead motor and means supporting the motor affording a container support, a container-agitator unit comprising an open top container and an agitator disposed in and connected with said container, means adapted 25 to afford a detachable driving connection between said motor and the upper end of said agitator, and resilient means urging the container-agitator unit downwardly to the container support when the agitator is operably detachably connected with said motor.

27. In a drink mixer, a supporting and driving unit comprising a fixed overhead motor and means supporting the motor affording a container support, a container-agitator unit comprising an open top container and an agitator disposed in and connected with said container, means adapted 30 to afford a detachable driving connection between said motor and the upper end of said agitator, and resilient means acting upon the container-agitator unit and tending firmly to clamp said container-agitator unit between the motor and the container support 35 when the agitator is operably detachably connected with said motor.

28. In a drink mixer, a supporting and driving unit comprising a fixed overhead motor and means supporting the motor affording a container support, a container-agitator unit comprising an open top container and an agitator disposed in and connected with said container, means adapted 40 to afford a detachable driving connection between said motor and the upper end of said agitator, and resilient means associated with the motor acting upon the container-agitator unit and tending firmly to clamp 45 said container-agitator unit between the motor and the container support when the agitator is operably detachably connected with said motor.

29. In a drink mixer, the combination

with a supporting and driving unit comprising 65 an overhanging motor, a standard by which the motor is fixedly supported and a container support afforded by said standard; a container-agitator unit comprising an open top receptacle and an agitator disposed in and connected with said receptacle; and cooperating clutch elements on the motor and agitator, the said standard being conformed and adapted by its engagement with the container to guide the clutch 70 elements into operative relation when the container-agitator unit is moved upwardly 75 along the standard.

30. In a drink mixer, the combination of 80 a container-agitator unit comprising an open top receptacle, a rotatable agitator carried in the receptacle and provided at its upper end with a clutch element; a supporting and driving unit comprising an overhead motor, a standard by which the motor 85 is carried and a clutch element on the motor, said standard being conformed and adapted to afford a support for the container-agitator unit and to serve as a guide for directing the agitator clutch element into operative 90 relation with the clutch element of the motor when the container is moved upwardly alongside the standard.

31. In a drink mixer, the combination of 95 a container-agitator unit comprising an open top receptacle and an agitator carried in and connected with said receptacle and occupying a position alongside of and adjacent to a portion of the side wall of the receptacle, a clutch element on the upper 100 end of the agitator, a supporting and driving unit comprising an overhead motor and its supporting standard, and a clutch element on the motor, said standard affording a support for the container-agitator 105 unit and serving as a guide to direct the aforesaid clutch elements into operative relation when that portion of the receptacle by which the agitator is carried is presented to the standard and moved upwardly along- 110 side of the standard.

32. A drink mixer agitator apparatus comprising a rotatable agitator shaft provided at its upper end with means facilitating its detachable connection with a driving motor, a bearing structure disposed closely adjacent to and alongside said shaft and affording bearings by which the said shaft is held in said bearing structure for rotation and means for firmly detachably 115 holding said bearing structure against the inner surface of the side wall of an open top receptacle with the bearing structure and shaft constituting no material obstruction to the top opening of the said receptacle. 120 125

33. A two unit drink mixer comprising a supporting-driving unit and a container-agitator unit, said supporting-driving unit

comprising an overhead motor, a supporting standard and switching mechanism controlling operation of the motor carrier by the standard and comprising a part constituting a yielding support for the container-agitator unit, the container-agitator unit comprising an open top receptacle and an agitator disposed in and connected with the receptacle to be manipulated by and with the receptacle in the several positions which the latter may assume in rinsing or service and cooperating clutch elements carried by the motor and the upper end of the agitator.

In witness whereof, we hereunto subscribe our names this 6th day of February, 1924.

E. M. THOMPSON.

comprising an overhead motor, a supporting standard and switching mechanism controlling operation of the motor carrier by the standard and comprising a part constituting 5 a yielding support for the container-agitator unit, the container-agitator unit comprising an open top receptacle and an agitator disposed in and connected with the receptacle to be manipulated by and with the 10 receptacle in the several positions which the latter may assume in rinsing or service and cooperating clutch elements carried by the motor and the upper end of the agitator.

In witness whereof, we hereunto subscribe our names this 6th day of February, 1924.

RUSSELL A. BLISH.

STEPHEN J. POPLAWSKI.

Witnesses:

GEORGE C. SCHMITZ,
E. M. THOMPSON.

Certificate of Correction.

It is hereby certified that in Letters Patent No. 1,529,830, granted March 17, 1925, upon the application of Russell A. Blish and Stephen J. Poplawski, of Racine, Wisconsin, for an improvement in "Drink Mixers," errors appear in the printed specification requiring correction as follows: Page 1, line 14, for the word "as" read *at*; same page, line 51, for the word "an" read *in*; page 5, line 95, claim 15, for the word "buttom" read *button*; same page and claim, line 108, for the word "forward" read *toward*; and that the said Letters Patent should be read with these corrections therein that the same may conform to the record of the case in the Patent Office.

Signed and sealed this 28th day of April, A. D. 1925.

[SEAL.]

KARL FENNING,
Acting Commissioner of Patents.
